(57) **CLAIM**

The ornamental design for a leakage containment apparatus for trash hauling vehicles, as shown and described.

DESCRIPTION

FIG. 1 is a front perspective view of a leakage containment apparatus for trash hauling vehicles showing my new design;

FIG. 2 is a top plan view thereof;

FIG. 3 is a left side elevational view thereof;

FIG. 4 is a bottom plan view thereof;

FIG. 5 is a rear elevational view thereof;

FIG. 6 is a front perspective view of a second embodiment of my new design of FIGS. 1-5 for a leakage containment apparatus for trash hauling vehicles;

FIG. 7 is a top plan view thereof;

FIG. 8 is a left side elevational view thereof;

FIG. 9 is a bottom plan view thereof;

FIG. 10 is a rear elevational view thereof;

FIG. 11 is a front perspective view of a third embodiment of my new design of FIGS. 1-5 for a leakage containment apparatus for trash hauling vehicles;

FIG. 12 is a top plan view thereof;

FIG. 13 is a left side elevational view thereof;

FIG. 14 is a bottom plan view thereof; and,

FIG. 15 is a rear elevational view thereof.
